[57] CLAIM

The ornamental design for a vent which attaches to the
rear of a clothes dryer and connects to the outlet in a
wall, as shown and described.

DESCRIPTION

FIG. 1 is a perspective view of a vent which attaches to
the rear of a clothes dryer and connects to the outlet in
a wall showing our new design;

FIG. 2 is an enlarged side elevational view thereof;

FIG. 3 is an enlarged bottom plan view thereof;

FIG. 4 is an enlarged top plan view thereof;

FIG. 5 is an enlarged end elevational view of one end
thereof; and,

FIG. 6 is an enlarged end elevational view of the second
end thereof.

The second side view is a mirror image of FIG. 2.

FIG. 1
